DS369

305

5,369

UNITED STATES PATENT OFFICE.

JAMES L. JACKSON, OF NEW YORK, N. Y.

DESIGN FOR MANGER.

Specification forming part of Design No. 5,369, dated November 21, 1871.

To all whom it may concern:

Be it known that I, JAMES L. JACKSON, of the city and State of New York, have made a new and original Design for a Manger; and the following is declared to be a correct description thereof.

This design relates to a lattice-work in cast-iron below the top-plate, forming one side of the hay-box or manger. The bottom and one side may also be open-work; but my present design only relates to the design or configuration of the said lattice-work.

In the drawing a perspective view is shown of the manger. My design, in this case, does not relate to the top plate *a* nor to the feed-box *b*. The open-work of the cast-iron side *d* of the manger or hay-box is made in imitation of wrought-

iron grating, such imitation forming a lattice-work, and the same is bounded by metal bars, and the bar *e* at the bottom is rounded, as shown in the drawing.

This open-work lattice is strong and very cheaply made.

I claim as my invention—

The design of the open-work lattice cast-metal side of the manger, substantially as shown in the drawing.

Signed by me this 13th day of July, A. D. 1871.

JAMES L. JACKSON.

Witnesses:

HAROLD SERRELL,
GEO. T. PINCKNEY.
